(57) **CLAIM**

The ornamental design for a multifunction tool, as shown and described.

DESCRIPTION

The invention described here may be made, used and licensed by and for the U.S. Government for governmental purposes without paying royalty to us.

FIG. 1 is a front, left, top isometric view of a multifunction tool;

FIG. 2 is a front elevation view of the multifunction tool;

FIG. 3 is a rear elevation view of the multifunction tool;

FIG. 4 is a top plan view of the multifunction tool;

FIG. 5 is a bottom plan view of the multifunction tool;

FIG. 6 is a left side elevation view of the multifunction tool;

FIG. 7 is a right side elevation view of the multifunction tool;

FIG. 8 is a front, left, top isometric view of the multifunction tool, wherein appendages which are normally secured in the interior of the housing of the multifunction tool are illustrated;

FIG. 9 is a rear, left, top isometric view of the multifunction tool, wherein the appendages which are normally secured in the interior of the housing are illustrated;

FIG. 10 is a front, right, top isometric view of the multifunction tool, wherein the appendages which are normally secured in the interior of the housing are illustrated;

FIG. 11 is a rear, right, top isometric view of the multifunction tool, wherein the appendages which are normally secured in the interior of the housing are illustrated; and

FIG. 12 is a front, right, bottom isometric view of the multifunction tool, wherein the appendages which are normally secured in the interior of the housing are illustrated; and,

FIG. 13 is a rear, right, bottom isometric view of the multifunction tool, wherein the appendages which are normally secured in the interior of the housing are illustrated.

Views are orthogonal projections unless otherwise noted.
